(57) **CLAIM**

The ornamental design for an arithmetic and control unit, as shown and described.

DESCRIPTION

FIG. 1 is a front elevational vieww of an arithmetic and control unit showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof;

Portions of FIG. 2 that are shown as broken lines are for illustrative purposes only and form no part of the claimed design.
